Patented May 30, 1922.

Fig. 1.

Fig. 3.

Fig. 4.

Fig. 6.

This technical drawing shows a cross-section of a structure, possibly a bridge pier, with the following dimensions and features:

- Left side: A vertical column with a horizontal top plate. A diagonal brace extends from the top of the column to the top of the plate. The vertical height of the column is labeled $21'$. The horizontal length of the top plate is labeled $20'$. The angle of the diagonal brace is labeled $24'$.
- Right side: A vertical column with a horizontal top plate. A diagonal brace extends from the top of the column to the top of the plate. The vertical height of the column is labeled $23'$. The horizontal length of the top plate is labeled $28'$. The angle of the diagonal brace is labeled $21'$. A horizontal dimension line between the two columns is labeled 6 .
- Bottom: A horizontal base with a central vertical support. The horizontal length of the base is labeled $28'$. A horizontal dimension line between the two ends of the base is labeled 6 .

ATTORNEY.

UNITED STATES PATENT OFFICE.

CHESTER F. GAILOR, OF BROOKLYN, NEW YORK.

WELDED JOINT.

1,418,071.

Specification of Letters Patent. Patented May 30, 1922.

Application filed July 16, 1921. Serial No. 485,251.

To all whom it may concern:

Be it known that I, CHESTER F. GAILOR, a citizen of the United States, and resident of Brooklyn, in the county of Kings and State of New York, have invented certain new and useful Improvements in Welded Joints, of which the following is a specification.

My present invention relates to welded joints, particularly for railroad rails, and has for its object to provide a joint which will combine great strength with a certain degree of flexibility which has been found a very desirable and practically necessary feature if the best results are to be obtained in actual service. My invention also has for its object to place the fish plates in such positions that they are readily accessible and will therefore give an opportunity for the best workmanship in welding. Another object of my invention is to weld the plates in a particular novel sequence or manner which will enhance the good qualities of the finished connection.

Two typical and satisfactory embodiments of my invention will now be described in detail with reference to the accompanying drawings, and the novel features will then be pointed out in the appended claims.

While the invention is illustrated in its application to joints for railroad rails, it will be evident that other structural members may be connected in a corresponding manner.

Figure 1 is a side elevation of a welded rail joint made according to my invention; Figure 2 is a horizontal section on line 2—2 of Figure 1; Figures 3 and 4 are vertical sections on lines 3—3 and 4—4 respectively of Figure 1. Figure 5 is a side elevation, and Figure 6 is a cross section on line 6—6 of Figure 5, illustrating another form of my invention.

In the construction shown in Figures 1 to 4, the webs of the two rail ends to be joined are designated by 20 and 20' respectively, their heads as 21 and 21', and their bases as 22 and 22'. The rail 20, 21, 22 is on the so-called "receiving" side of the joint, that is to say, the side toward which the traffic moves as indicated by the arrow.

The splicing plates or fish plates which are welded to the rail ends are of novel formation and arrangement. Each of these plates comprising a central portion 23, of proper height to fit between the bases and the heads

of the rails, and preferably flat or plane as shown. The end portions 24 and 25 of the plates are adapted to fit against the webs of the rails, on opposite sides; these end portions are of considerably smaller height or width than the central portions 23, so that the upper and lower edges of said end portions will be at a distance from the rail heads and rail bases respectively. The end portions 24, 25 of the same plate are in the same plane, with each other, but not with the corresponding central portion 23, and the connection between said central portion and the end portions is effected by laterally bent intermediate portions 26, 27 respectively. While each of the end portions 24, 25 is symmetrical to the horizontal plane in which the section 2—2 is taken, they are not alike, but one of them, 24, is higher or wider than the other, 25, their length, however, being the same as indicated at X. The upper edge of the central portion 23 is shorter than its lower edge, both of them, however, being preferably symmetrical relatively to the distance of their ends from the extremities of the plate, as is indicated by the equality of the two horizontal distances indicated at Y in Figure 1 (bearing in mind that, as stated above, the lengths X of the two end portions 24, 25 are equal).

The two plates which are located on opposite sides of the rail webs are used in reversed positions, (Figures 1 and 4); that is to say, the rail web 20 is engaged by the wide end portion 24 of one plate and by the narrow end portion 25 of the other plate, while the rail web 20', is engaged on opposite sides by the narrow end portion 25 of the first-named plate and the wide end portion 24 of the second named plate. The purpose of this arrangement is to avoid making welds on opposite sides of the webs in the same location, that is, at the same level, since in that case the strength of the rail sections would be reduced.

The car traffic being, generally, of such a nature as to be practically always in the same direction on the same track, it is highly desirable and almost necessary to provide more plate bearing surface on the "receiving" side of the joint. For this purpose, the fish plates are shifted toward said receiving side, so that the medium vertical plane M of the plates will not coincide with the plane of the rail ends, but will be on the receiving side of such ends, as indicated by the distance Z

in Figures 1 and 2. For instance, in practice, with 7 inch T rails so commonly used, the short upper edge of the central portion 23 might be about 12 inches, of which 4 inches on the rail shown at the left hand in Figure 1, and 8 inches on the receiving rail. The long lower edge of the central portion 23 might in this case be about 18 inches, of which the greater part, for instance 11 inches, on the 10 "receiving" rail, and 7 inches on the other rail. By having the lower edge of the central portion 23, where it is in contact with each rail, longer than that part of the upper edge of the plate which is in contact with 15 the same rail, the joint structure is given a better support, and the stresses are distributed over a larger area.

The shape of the plate will be varied to suit the various rail shapes, but generally 20 speaking, the support at the rail ends must be such as to give adequate support and strength to the structure. For convenience in manufacturing and welding, the end portions 24 and 25 of the plates are preferably 25 of rectangular shape, so as to have the weld lines on the webs of the rails, in readily accessible locations, thereby facilitating welding work of high quality.

Figure 3 shows that the fish plates are 30 fitted to the rails in such a manner as to produce a box girder structure having a maximum strength at the joint, and also that the welds connecting the plates with the bases and heads of the rails are in readily 35 accessible location, thus again giving a better opportunity for good workmanship in welding. The importance of careful and efficient welding in structures of this character will be obvious.

40 It is further important that the plates be short enough to avoid producing a long rigid structure which would interfere with the necessary wave motion in the tracks. Still, the structure should have ample 45 strength to withstand the most severe service. The general shape of the plates, and particularly the way they are fitted and welded to the rails is a very important feature of my invention, and particularly when 50 the welding is performed in the particular novel manner and order set forth below, it will be found that the structure will produce many results, asserted to be present in many other rail joints, but found lacking therein, 55 which are of the greatest advantage in a practical solution of the problems involved. As indicated in the drawings, the welds proper 28 are not continued along the entire edge or outline of the plate, but only along 60 its horizontal upper and lower edges, and along the horizontal edges of the end portions 24, 25, so that the curved or laterally bent connecting portions 26, 27 of the plates remain unwelded at their edges, thereby giving 65 the structure the correct and highly

beneficial amount of flexibility which recent practical experience has shown to be necessary in welded joints in order to obtain the best practical results in actual service.

The preferred way of welding the structure shown, in order to secure the best distribution of stresses and other advantages as explained below, is as follows: Starting at the point 1, where the upper edge of the central plate portion 23 is in contact with the 70 end of the rail head 21, the welding would proceed along said upper edge, and said rail head to the end of said edge at 2. This would be done either simultaneously or successively with both fish plates. Then the 75 lower edges of the central portions 23 of both plates would be welded either simultaneously or successively to the base 22 of the same rail, beginning at the rail end 4 and proceeding away from the said end, to 80 the end 5 of the said lower edge. The next weld would be made on the same rail, along the end portion 25 of one plate, and the end portion 24 of the other plate, to join them either simultaneously or successively, to the 85 web 20 of the same rail, and in this case also, the welding operation would preferably proceed in a direction away from the rail ends, that is to say, it would start at the junction 90 of said end portion 25 with the connecting portion 27, and be continued until the free end of the end portion 25 is reached, as at 8. The plates would thereupon be welded to the other rail by first welding the remaining portion of the upper edges of the plates to 95 the rail head 21', beginning at the rail end 1 and proceeding to the end 3 of said edge. Then the remaining portions of the lower edges of the plates would be welded to the base 22', beginning at the rail end 4 and proceeding to the end 6 of the central portion 23, and finally the end portions 24 and 25 of the two plates would be welded to the web 20' of the rail, preferably beginning at the 100 end 9 nearest to the ends of the rails, and proceeding in a direction away from the rail ends, to the free end of said portions, 24 and 25. I desire it to be understood, however, that the fish plates might be welded to the rail bases first, and then to the rail heads 105 and to the webs.

110 This particular method of welding equalizes the vertical actions caused by the welding operation, and also produces a powerful longitudinal action to hold the abutting rail ends in compression. Another advantage 115 results from the fact that the plates and rails are welded together while they are expanded in like or proportional amounts. The plates might be heated before applying 120 them to the rails, and such preheating would benefit the joint structure, but is by no means necessary, as with reasonable care the welding 125 done in the manner specified above will produce the desired results. As the struc- 130

ture cools after the welding has been completed, the central portion 23, between the points 2, 3, 5 and 6 will by contraction be drawn toward the webs of the rails, thus 5 relieving the vertical stresses and also insuring a strong tightening effect in the proper direction to withstand the service and climatic stresses so dangerous to such joint structures.

10 The end portions 24 and 25 of the plates are not necessarily rectangular, all that is required being that they shall suitably fit the sides of the rail webs and also easily admit of the welding, so long as the curved 15 or bent connecting portions 26, 27 are able to function properly.

The plates should be so formed as to insure contact of the end portions 24, 25 with the webs of the rails before the main or central portion 23 has become lodged in place 20 firmly by drawing up the bolts 29 (Figures 1 and 2). I thus avoid the necessity of using additional bolts or fasteners in the other portions of the plates. The bolts 29 need not 25 form a permanent part of the joint, but may be removed after the welding operation.

Owing to the flexibility of the unwelded 30 plate portions 26, 27, no failures will occur through the welds along the upper or the lower edges of the plates, or just outside the ends of the plates, at the junction of the bare rail portions with the portions reinforced by the plates. Such failures are very 35 liable to occur in prior structures in which the joint structure is of excessive rigidity.

Another embodiment of my invention, which has the same advantage of great 40 strength with a proper amount of flexibility, is shown in Figures 5 and 6. Here the central portions 23' of the fish plates extend from the rail heads to the rail bases, and bridge the joint between the ends of the rails. The ends of the fish plates are forked 45 so as to form narrow portions as indicated at 24' and 25', thereby obtaining the desired flexibility, particularly in a vertical direction. The welds 28' in this case may be exclusively in horizontal lines, along the upper 50 and the lower edges of the plates, in their full length, to connect them with the heads and bases of the two rails. Figure 5 shows the fish plate located symmetrically with 55 reference to the rail ends, which is the arrangement to be used when traffic is in both directions on the same track. It will be understood that where traffic is always in one direction only, an unsymmetrical arrangement, as explained with reference to Figures 60 1 and 2, would be adopted for the fish plate of Figure 5. Similarly, if the construction shown in Figures 1 and 2 were to be used on a line having a single track (traffic in both directions on the same rails), the fish 65 plates shown in said Figures 1 and 2 would

preferably be used in a position symmetrical with reference to the rail ends.

In either of its embodiments, my invention provides a very good electrical connection between the rails, so as to dispense with 70 wires, or other circuit completing devices at the joints.

Various modifications may be made without departing from the nature of my invention as set forth in the appended claims. 75

I claim:—

1. A structure comprising two aligning members and a plate bridging the joint between them, and having a relatively wide central portion welded to both members, 80 relatively narrow end portions welded individually to the different members, and unwelded connecting portions between said central portion and the said end portions.

2. A structure comprising two aligning 85 members and a plate bridging the joint between them and having central and end portions welded to said members and unwelded connecting portions between such central and end portions, said connecting portions 90 being bent laterally.

3. A structure comprising two aligning members and a plate bridging the joint between them and having a welded central portion, welded end portions lying in the 95 same plane with each other but laterally offset from the plane of the central portion, and unwelded connecting portions between said central portion and said end portions.

4. A structure comprising two aligning 100 members and a plate bridging the joint between them and having a relatively wide central portion welded to both members, relatively narrow end portions welded individually to different members, said end portions 105 being located in a plane different from that of the central portion, and unwelded laterally-bent connecting portions between said central portion and said end portions.

5. A structure comprising two aligning 110 members, and welded plates located on opposite sides of said members and bridging the joint between them, each plate having end portions and a central portion located in different planes, the central portions of 115 the two plates being farther apart than neighboring end portions of different plates.

6. A structure comprising two aligning members, and plates welded thereto located on opposite sides of said members and bridging the joint between them, each plate having end portions and a central portion located in different planes and laterally-bent connecting portions between said central portion and said end portions, the central 120 portions of the two plates being farther apart than the neighboring end portions of different plates.

7. A structure comprising two aligning members, and plates located on opposite 130

- sides of said members and bridging the joint between them, each plate having end portions and a central portion located in different planes and welded to said members, 5 and laterally-bent unwelded connecting portions between said central portion and said end portions, the central portions of the two plates being farther apart than neighboring end portions of different plates.
- 10 8. A structure comprising two aligning members, and plates bridging the joint between said members and located on opposite sides of said members, each plate having a relatively wide central portion welded to 15 both of said members, and relatively narrow end portions welded individually to different members, the distance between the central portions of the two plates differing from the distance between neighboring end portions of different plates.
- 15 9. A structure comprising two aligning members, and welded plates located on opposite sides of said members and bridging the joint between them, each plate having 20 end portions and a central portion located in different planes, the distance between the central portions of the two plates differing from the distance between neighboring end portions of different plates.
- 20 10. A structure comprising two aligning members, and plates welded thereto located on opposite sides of said members and bridging the joint between them, each plate having 25 end portions and a central portion located in different planes and laterally-bent connecting portions between said central portion and said end portions, the distance between the central portions of the two plates differing from the distance between neighboring end portions of different plates.
- 30 11. A structure comprising two aligning members, and plates located on opposite sides of said members and bridging the joint between them, each plate having end portions and a central portion 35 located in different planes and laterally-bent connecting portions between said central portion and said end portions, the distance between the central portions of the two plates differing from the distance between neighboring end portions of different plates.
- 35 12. A structure comprising two aligning members, and plates located on opposite sides of said members and bridging the joint between them, each plate comprising a central portion and end portions welded to said members, those end portions which are adjacent to each other on opposite sides of said 40 members, being of different width and having their weld lines out of registry.
- 40 13. A structure comprising two aligning members, and plates located on opposite sides of said members and bridging the joint between them, each plate comprising a cen-

tral portion and end portions welded to said members, those end portions which are adjacent to each other on opposite sides of said members having their weld lines out of registry.

70 14. A structure comprising two aligning members, and plates located on opposite sides of said members and bridging the joint between them, each plate comprising a central portion and end portions welded to said members, the two end portions of the same plate being of different width, and the two plates having their ends in reversed relation, so that the narrower end portion of one plate will be adjacent to the wider end 75 portion of the other plate.

80 15. A structure comprising two aligning rails, and plates located on opposite sides of said rails and having relatively wide central portions welded to the bases and to the heads of said rails, and relatively narrow end portions welded to the webs of said rails.

85 16. A structure comprising two aligning rails, and plates located on opposite sides of said rails and having relatively wide central portions welded to the bases and to the heads of said rails, and relatively narrow end portions welded to the webs of said rails, said central portions bridging the joint of the rails and being located unsymmetrically relatively to such joint, with the major portion of each plate on the "receiving" side of such joint.

90 17. A structure comprising two aligning rails, and plates welded thereto on opposite sides of the rails, said plates bridging the joint of the rails and being located unsymmetrically relatively to such joint, with the major portion of each plate on the "receiving" side of the joint.

95 18. A structure comprising two aligning rails, and plates located on opposite sides of said rails and having relatively wide central portions with relatively short upper edges welded to the rail heads and with longer lower edges welded to the rail bases, and relatively narrow end portions welded to the webs of said rails.

100 19. A connecting plate for welded rail joints, having a relatively wide central portion located in a plane, and relatively narrow end portions located in a plane offset from that of said central portion to such an extent that when the end portions engage the webs of aligning rails on one side, said central portion will engage the heads and bases of said rails on the same side that the ends engage the webs.

115 20. A connecting plate for welded joints, having a relatively wide central portion and relatively narrow end portions, one of which is wider than the other.

120 21. A connecting plate for welded joints, having a relatively wide central portion and

relatively narrow end portions located in a plane different from the plane of said central portion, and laterally bent connecting portions between said central portions and 5 said end portions.

22. A fish plate for rails comprising a relatively wide central portion having a relatively short upper edge for engaging the rail heads, and a longer lower edge for en- 10 gaging the rail bases, and relatively narrow end portions for engaging the rail webs.

23. A fish plate for rails comprising a relatively wide central portion having a relatively short upper edge for engaging the rail heads, and a longer lower edge for en- 15 gaging the rail bases, and relatively narrow end portions for engaging the rail webs, one of said end portions being wider than the other.

24. The method of connecting aligning members, which consists in first welding a connecting plate to one of said members, the welding action being started at the end of 20 such member, and proceeding away from

such end, and then welding said connecting 25 plate to the other member, such second welding action likewise beginning at the end of the member, and proceeding away from such end.

25. The method of connecting aligning 30 rails, which consists in welding a connecting plate first to one of said rails, such first welding action starting at the end of one member, at the head of the rail, and proceeding away from such end, along said head, the welding 35 action being then performed at the base of the same rail, beginning at the end of the rail and proceeding away from it, and such welding action being completed along the web of the same rail, beginning relatively 40 near the rail end and proceeding in a direction away from such end, and thereupon welding the plate to the other rail by a corresponding series of operations.

Signed at New York, in the county of 45 New York and State of New York, this 28 day of June, A. D. 1921.

CHESTER F. GAILOR.
